UNITED STATES PATENT OFFICE.

HENRY C. HARRIS, OF COLUMBUS, OHIO.

DUPLICATING-MACHINE.

No. 921,244.

Specification of Letters Patent.

Patented May 11, 1909.

Application filed June 12, 1908. Serial No. 438,013.

To all whom it may concern:

Be it known that I, HENRY C. HARRIS, a citizen of the United States, residing at Columbus, in the county of Franklin and 5 State of Ohio, have invented certain new and useful Improvements in Duplicating - Machines, of which the following is a specification.

My invention relates to the improvement of 10 duplicating machines of that class which are employed for the purpose of making duplicate copies of typewritten letters by the aid of a perforated cylinder and stencil sheet thereon, and has particular relation to that 15 class of duplicating machines known as mimeographs.

The objects of my invention are to provide 20 a duplicating machine of the class set forth with improved means for rapidly printing reproductions of circulars, letters etc., on a 25 continuous strip of paper fed from a paper roll; to provide improved means for automatically cutting the paper strip into sections after the printing operation; to provide 30 improved means for stopping the traveling movement of the paper strip during the cutting action and to produce other improvements the details of construction and arrangement of parts of which will be more fully pointed out hereinafter.

These objects I accomplish in the manner illustrated in the accompanying drawings, in which:

Figure 1 is a side elevation of my improved 35 duplicating machine, Fig. 2 is a front end view thereof, Fig. 3 is a detail view in perspective of the delivery plate and adjacent parts, Fig. 4 is a plan view of the machine, Fig. 5 is a sectional view on line $y-y$ of Fig. 40 1, Fig. 6 is a side elevation of that portion of the machine which carries the printing cylinder showing a portion of the outer cylinder 45 supporting frame broken away and other adjacent parts removed for the sake of clearness in illustration, and, Fig. 7 is a central longitudinal section on line $x-x$ of Fig. 4.

Similar numerals refer to similar parts throughout the several views.

In carrying out my invention I employ a 50 suitable oblong supporting base frame 1, upon the rear portion of which is mounted the mimeograph supporting frame, which comprises opposing side frame pieces 2 in which are journaled the end spindles 3 of the 55 usual form of mimeograph cylinder 4, the ends 4^a of which have the forms of spoked

wheels. Between these wheel members is carried a segment of a cylinder which is indicated in Fig. 7 at 5, said segment being provided with the usual ink outlets or perforations. On one of the stub shafts or end spindles 3 of the cylinder is carried a gear wheel 6 which meshes with the teeth of a pinion 7 which is carried on a short horizontal shaft 8 mounted in a sleeve or boxing 60 9 which is supported from the adjacent side frame 2. On the outer end of the shaft 8 is carried a comparatively large grooved belt or pulley wheel 10, over which an endless belt or cord 11 runs to the belt wheel of a suitable 65 electric motor 12 which is preferably located in rear of the frame base 1 upon a rearward extension 1^a of the latter.

At a suitable distance in rear of the base frame 1, I support a vertical standard 13 75 in which is journaled a sleeve or tubular body 14 (see Fig. 5) the latter being adapted to be fixed in its position by set screws 15. Journaled in the sleeve or bearing body 14 is the outer portion of a horizontal rod 16, 80 the end portions of which are threaded, as shown. Each end of the bearing body 14 is formed with a shallow ball-race 17 and upon the outer portion of the shaft 16 is screwed a bearing ring 18, the latter being 85 made to abut against the outer end of the bearing body 14 and provided with a ball-race in its abutting face within which and the race 17 are contained bearing balls 19, the latter being in contact with the shaft 16. 90 Bearing balls 20 are likewise contained in the race-way 17 at the inner end of the bearing body 14 and in a corresponding race-way of a bearing ring 21 which is mounted on the shaft 16. The ring 21 abuts against a disk 22 which is mounted centrally on the shaft 16 and which in turn bears against the outer face of a tapering reel or paper roll plug 23. The shaft 16 in its outer end portion also passes through a second tapering reel plug 24 100 against the outer face of which bears a plate or disk 25 against which bears a washer 26 which is held in place by a nut 27 carried on the threaded outer end of the shaft 16. Upon the tapering reel plugs 24 is mounted in the 105 usual manner a paper roll 28.

Extending rearwardly from and pivoted between the lower portions of the side frame members 2 is a rearwardly extending platform 29 above the outer end portion of which 110 is suitably journaled a guide roller 30.

31 represents a yoke-shaped wire frame

which has the ends of its side arms fixed in connection with the rear end and outer portions of the platform 29, said yoke-shaped frame having journaled in its outer or rear 5 end portion a roller 32, the latter bearing upon the upper side of the paper roll body 28. Affixed to a transverse rod 33 which bridges the platform or board 29 are forwardly and downwardly inclined guide fingers 34, the 10 upturned lower portions of which bear upon the paper strip 28^a which leads from the roll 28 on to the platform 29 beneath the roller 30. From the forward end of the platform 29, the paper strip leads over a 15 transverse plate 35 thence between the underside of the printing cylinder 5 and a transverse pivoted roll 36. From this roll, the paper strip leads forwardly over a fixed horizontal delivery plate 37 which is supported below and in front of the printing cylinder from the framework 1 and which has projecting from its upper side near each of its longer edges, a vertical guide flange 38.

Supported transversely upon the framework 1 at the forward end thereof and below a forward lip extension 37^a of the delivery plate 37 is a horizontal plate or bar 39 and rising from opposite ends thereof are the upturned members 40^a of angular brackets 25 40. These brackets have their base or horizontal members adjustably mounted on the plates 39 by having formed therein slotted openings 41 through which screws 42 pass into said plate 39. In one of the brackets 35 40 is fixed the shank of an outwardly inclined shearing blade 43 having its sharpened edge uppermost and its point engaging an opening in the member 40^a of the remaining bracket 40.

40 44 represents a second cutting or shearing blade which in its outer or rear portion is pivoted to the inner side of the outer end portion of the blade 43. Fixed to the rear side of the blade 44 near its outer end is an 45 extension 45^a of an angle bar 45 which angle bar extends at an angle with the blade 44 and on the inner or rear side of the fixed blade 43 (see Figs. 4, 1 and 7). The purpose of this angle bar 45 is to form a paper 50 guide which is carried by the blade 44.

Extending transversely above the delivery plate 37 and pivoted in the side flanges 38 is a rod 46 which is provided with downwardly projecting paper guide fingers 47. 55 Immediately in rear of the rod 46 is provided a transverse bar 48 said bar having upwardly and outwardly bent hook terminations 48^a which bear upon the upper sides of the flanges 38 and which are prevented 60 from an undesirable degree of upward movement by angular stop lugs 49, the upper horizontal portions of which extend over the hook terminations of said bar. The bar 48 is adapted to be made to bear upon the 65 paper strip 28^a which extends over the de-

livery plate 37 in the manner hereinafter described. Pivoted to the center of the length of the bar 48 is one end of a lever bar 50 having its outer portion pivoted to an upward bracket 51 which projects from the framework 1 at one side of the delivery plate. On the outer side of its pivot point which is indicated at 50^a, the lever 50 is rigidly connected with one end of an upwardly inclined arm 52.

53 represents an operating bar or lever which is pivoted at 54 to a forward and upward extension of one of the frame members 2, the rear portion of said bar extending on the inner side of said frame member 2 with 80 its upper side in the path of a roller 55 which is pivoted on the adjacent cylinder end at one side of the end spindle of the latter. The arm 53 which extends forwardly and laterally from its pivot point has its outer 85 end connected through the medium of a rod 56 with the outer end or shank 44^a of the shear or cutting blade 44. With the outer end portion 44^a of the cutting blade is connected one end of a spring 57, the remaining 90 end of which is connected at a lower point with the frame 1, said spring tending to normally hold said cutting blade in the inclined elevated position shown in Fig. 2 of the drawing. The outer portion or shank of the 95 cutting blade is limited, however, in its downward movement by contact with a suitable bumper 58 which is mounted in the outer portion of an arm 59 which projects from the frame 1.

60 represents a spring, one end of which is connected with the bar 53 and the remaining end of which is connected with the outer end of the lever 50.

In front of and below the forward end of 105 the machine body, I provide a suitable paper receiving tray 61.

In order to insure a proper guiding of the paper strip between the roller 36 and the printing cylinder, I provide on each side of the plate 35 angular guide brackets 62 the horizontal portions of the latter being slotted to receive screws 63 which are adapted to enter the framework of the machine. The upturned inner members of the guide 110 brackets 62 are designed to limit the lateral movement of the paper strip and said brackets being adjustable, it is obvious that they may be made to accommodate strips of different widths.

In operation, it will be understood that 115 rotary motion is imparted to the wheel 10 from the motor 12 and through the shaft 8 and gear wheels 7 and 6 to the cylinder 4. In producing printed reproductions from machines of this class, I follow the usual 120 custom of covering the perforated cylinder segment 5 with a pad of cloth or suitable ink absorbing material such as is indicated at 5^a, said pad being covered by a stencil 130

sheet 5^b in which the words to be printed, have been stenciled in the usual manner. The ink as usual is applied to the inner surface of the cylinder segment and finds its way through the perforations of the latter, thence through the pad 5^a and the stencil openings of the sheet 5^b. This construction is well known, however, and does not form a part of my invention.

10 The binding of the paper strip between the cylinder segment and the roll 36, results in an intermittent forward feeding movement of the paper strip, during which movements of the paper, printed impressions are made thereon from the stencil sheet in the usual manner. From the roller 36, the paper strip passes outward over the delivery plate and thence over the angle bar 45 and fixed cutter blade 43. It will be understood that 15 once during each rotation of the cylinder, the roller 55 will come into contact with the upper side of the rear portion of the bar 53, resulting in depressing the rear portion of said bar and raising the forward portion 20 thereof, this raising action resulting through the spring connection 60 in an upward movement of the outer portion of the lever 50 and a downward movement of its inner portion, which in turn causes the bar 48 to drop 25 downward on to the paper strip and hold the latter in contact with said delivery plate. As this is accomplished, the upward pull on the connecting rod 56, which necessarily follows the upward movement of the bar 53, 30 results in a downward swinging movement of the blade 44 which shearing against the fixed blade 43, causes the paper to be severed, permitting the severed sheet or section to drop into the receptacle 61. As the roller 35 passes out of contact with the bar 53, it is obvious that through the action of the spring 57 the outer end of the bar 53 will be again pulled downward and through pressure thereof on the arm 52, the bar 48 will be 40 raised out of contact with the paper strip. As this is accomplished, the contact of the cylinder segment and paper strip is again effected, with the result that the paper strip is fed forward the length of another section 45 thereof, at which time the operation of severing said section from the strip and holding the strip against movement, is repeated. As the paper is wound from the roll 28 and the circumference of said roll reduced, it is obvious 50 that the roller 32 together with the wire frame 31 and platform 29 will be lowered accordingly and it will also be understood that during the movement of the paper from the roll to the cutting blades, the paper strip will be held against buckling and in proper contact with the supports over 55 which it travels by the roller 30, the fingers 34 and fingers 47. In order to prevent the paper strip from becoming depressed between the outer edge of the delivery plate

and its point of severance, I have provided the angle bar 45 which being connected with the blade 44, descends below the fixed blade 43 when the blade 44 moves downward, but which when said latter blade is elevated, 70 forms a bridge or support for the paper strip.

In case a paper roll of less or greater width is desired for use, it is evident that the space between the reel end plates 22 and 25 75 may be decreased or increased by turning the outer nut or bearing member 18 inward or outward on the threaded portion of the rod 16. It will also be understood that the length or size of the paper section cut from the strip at the forward end of the machine, 80 may be varied by moving the brackets 40 outward or inward, thereby changing the position of the fixed blade 43.

I am aware that mechanism for producing 85 a plurality of printed reproductions has been employed in which a printing cylinder such as herein described, is embodied, but the operation of such machines has usually consisted in feeding previously cut paper sections or sheets under the printing cylinder.

By the operation and construction which I have described, it will readily be understood that simple and improved means are provided for automatically feeding a paper strip 95 beneath the printing cylinder, successively producing printed impressions thereon and cutting said paper strip into sections.

What I claim, is:

1. In a machine of the character described, 100 the combination with a rotatably mounted printing cylinder, a feed roller and a delivery plate, of a paper cutting mechanism in front of said delivery plate comprising a fixed cutting blade and a pivoted cutting blade, a bar connected with and extending at an angle 105 from said pivoted cutting blade and adapted when the latter is elevated to fill the space between the end of the delivery plate and the fixed blade, said bar serving as a support for 110 the paper in its passage from the delivery plate to the fixed cutting blade and means for operating said pivoted blade from the cylinder.

2. In a machine of the character described, 115 the combination with a rotatably mounted printing cylinder, a feed roller adjacent thereto and a delivery plate extending in front of said cylinder, of a paper cutting mechanism in front of the delivery plate comprising a 120 fixed cutting blade and a pivoted cutting blade, a bar extending across said delivery plate, means for operating said pivoted blade, and means operated from the cylinder for raising said bar during the printing operation and lowering the same during the cutting operation.

3. In a machine of the character described, 125 the combination with a rotatably mounted printing cylinder comprising a perforated 130

cylinder segment and a projection on one end of said cylinder, a feed roller journaled adjacent to said cylinder, and a delivery plate extending in front of the cylinder, of a paper severing mechanism in front of the delivery plate comprising a fixed cutting blade and a pivoted cutting blade, a pivoted bar having one end extending in the path of said cylinder end projection and its remaining end connected with the movable cutting blade, and a paper strip carrying reel journaled in rear of said printing cylinder.

4. In a machine of the character described the combination with a rotatably mounted printing cylinder a portion of which is cut away, of a feed roller lying adjacent said cyl-

inder, a delivery plate, a paper cutting mechanism in front of said delivery plate comprising a fixed cutting blade and a pivoted cutting blade, a clamping device adapted to clamp the paper to the delivery plate while it is being cut, yielding means actuated from the cylinder for operating said clamping device and positive means also actuated from the cylinder for actuating said cutting blade. 25

In testimony whereof I affix my signature in presence of two witnesses.

HENRY C. HARRIS.
